UNITED STATES PATENT OFFICE.

SAMUEL G. HIBBEN, OF BLOOMFIELD, NEW JERSEY, ASSIGNOR TO GEORGE CUTTER COMPANY, A CORPORATION OF INDIANA.

LIGHTING FIXTURE.

Application filed January 27, 1921. Serial No. 440,462.

To all whom it may concern:

Be it known that I, SAMUEL G. HIBBEN, a citizen of the United States, and a resident of Bloomfield, in the county of Essex and the State of New Jersey, have invented a new and useful Improvement in Lighting Fixtures, of which the following is a specification.

This invention relates to lighting fixtures. The object of the invention is to furnish a support for lamp shades or globes, and particularly shades or globes for use with the so-called nitrogen lamp, and for globes or shades which are closed at the bottom.

A further object is to furnish a three-point support in a form that will hold the globe or shade in stable position, but from which the globe or shade may be readily removed without the necessity of loosening any set screws or other fixed parts. Another object is to make such a fixture in a form that will be thoroughly ventilated, dust-proof, neat in appearance, easily and cheaply manufactured, and of an ornamental design.

Referring to the drawings Fig. 1 is a side elevation and partial vertical section through a fixture embodying this invention; and Fig. 2 is a vertical horizontal section on the line 2—2, of Fig. 1.

The fixture is normally suspended by a chain 1, the lower link of which is attached to a ring member 2, which screws into a collar member 3, which supports a spider member 4, having a plurality of downwardly extending straps 5, terminating in a band or collar 6. Supported by this band or collar 6 is a tubular casing member 7 having an internal inturned flange 8 at its upper edge. Mounted upon the upper side of this flange 8 is a felt washer 9 attached to the flange by suitable pins 10. The collar member 6 is attached to the casing 7 by means of rivets 11, or by any other suitable means. At its lower end of the casing member 7 is flared outward and formed into three lateral wings 12, which are illustrated in vertical section in Fig. 1, and in plan view in Fig. 2. Just above these wings, and in the tubular part of the casing a number of perforations 13

are provided through the casing, for ventilation. The wings 12 are flared outward forming a slightly inclined outwardly extending portion 14, which at its outer limit is turned vertically downward forming a shoulder 15. Beyond this shoulder the wings are again extended outward and slightly downward forming terminal inclined portions 16. This construction is clearly illustrated in Fig. 1 in the sectional part. It will be understood that the members 12 while referred to as wings, may be of any desired form or width, and may be reduced to mere rods. Likewise that the member 15, shown as a shoulder, may be merely a hump, or any upwardly extending member adapted to engage the edge of the globe or shade to prevent lateral movement thereof.

A sleeve member 20 is slidably mounted on the outside of the casing member 7, and is large enough to slide freely up and down thereon, and also to slide over the straps 5 for removal from the fixture without detachment of any parts. Near its upper edge the sleeve member 20 has formed a raised annular band 21, for ornamental effect. Towards its lower end the sleeve member is flared outwardly forming a sloping wall 22, and through this flared portion 22 are provided a number of ventilating perforations 23. A metal projection in the form of a spring 24 or similar member may be attached to the inside of the sleeve member, that will hook above the ring 6, thus enabling the sleeve member to be hung in its raised position when globe is being removed. The flared portion 22 of the sleeve member terminates in a cylindrical portion 25, which has its lower edge turned back upon itself to form an ornamental flange or bead 26.

Supported by a threaded terminal 30 of the ring member 2 is a standard lamp socket 31, which is suitably arranged and wired to receive the threaded base of an incandescent electric lamp. This fixture is particularly designed for lamp bulbs of the type now commonly used for nitrogen lamps, which comprise an elongated neck 32 and enlarged bulb 34, the bulb surrounding the lamp

filament. The neck 32 of the lamp extends upward inside the tubular shell member 7, and the bulb is adapted to lie below the flared supporting members 12, as will be obvious.

The lamp globe or shade, surrounding the bulb 34 is used with the metal members above described. This member may vary in shape and construction, and may be simply a shade, entirely open at the bottom or a complete globe, having only a single opening at the top. In either case it is made with an opening at the top adapted to enclose and seat upon the supporting wings 12. In order that this may be done the globe or shade is made with an outwardly and downwardly extending upper portion 40, which extends inward to a substantially cylindrical terminal flange 41, which is a standard construction. This terminal flange 41 has an external annular groove 42, normally intended to receive set screws for supporting the shade or globe. Such annular groove, however, is standard construction and is not an essential part of the design. Globes or reflectors may be used without such annular groove if desired. In the present case the opening through the neck 41 of the globe is of a diameter slightly larger than the diameter of the shoulder portion 15 of the supporting member. Normally the underside of the flared portion 40 of the globe seats upon the upper side of the three supporting wings, in the position clearly illustrated in the sectional view of Fig. 1. The shoulder 15 prevents anything more than a slight lateral movement of the globe which is held in the position indicated by the weight of the globe. However, when the globe is lifted far enough for the underside of the portion 40 thereof to be higher than the top of the shoulder 15, the globe may then be moved laterally until the neck 41 comes into contact with the cylindrical wall 7 of the main casting. The supporting wings 12 are of such extent that when the globe is raised and pushed inward upon the flared portion 14 of the support, until its further movement is stopped by contact with the cylindrical shell 7, that thereafter a tilting of the globe downward on the side opposite that in which the globe and shell are in contact, will permit the supporting wing 12 on the free side to pass upward through the opening in the neck 41, and thus permits removal of the globe from its support without the necessity of taking out any screws, or the removal of any parts whatever from the fixture.

It will be observed that the sleeve 20 may be readily pushed upward with one hand of the operator, to permit the globe to be shifted laterally to remove it from its support; and that when the globe is in normal position as shown in Fig. 1, and the sleeve 20 is brought down to its normal position,

cooperating with the shoulder 15, it locks the globe in position so that it cannot be shifted laterally to a point where it can be removed from the fixture. In other words, the sleeve 20 acts as a lock against accidental removal of the globe from the fixture. It also acts as a lock in case the globe should be accidentally raised, since in such cases the sleeve 20 would still be in engagement with the neck 21, and would prevent its lateral shifting, and when the pressure from beneath was removed the globe would settle back to its normal position.

This fixture gives a three-point support for the globe or shade, ensuring its stable position at all times. The arrangement of collars 3 and 6 and connecting straps 5 leaves an opening for access to the socket 31, for wiring that member, and also for the protrusion of a switch key, if desired. These straps also add to the ornamental appearance of the fixture and reduce the amount of the metal required. This strap construction is not objectionable on account of dust, since the felt washer 9 seals the lower part of the lamp against admission of dust through the openings between the straps. The lamp is self ventilating by means of openings 13 and 23. The sleeve 20 may be readily raised and held up by one hand of the operator while the shade is being removed or replaced.

The many uses and advantages of the invention will be apparent to those familiar with the art.

I claim:

1. A lighting fixture comprising a supporting member, a lamp socket attached thereto, straps attached to the support and carrying a cylindrical perforated shell member surrounding the lamp socket, a packing member between the shell and socket and above the perforations in the shell to prevent passage of hot air therebetween, said shell member extending downward around the socket and having its lower portion flared out to form a three-point support for a lamp globe or shade, and a freely slideable cylindrical perforated sleeve mounted on the outside of the said shell, the lower portion of the said sleeve being flared out and turned down to form a cylindrical portion adapted to engage the flange of a lamp globe or shade to prevent lateral movement thereof.

2. In a lighting fixture, the combination of a supporting member, a lamp socket attached thereto, a suspended unit having a central flanged opening at its top, a depending perforated shell attached to said supporting member and surrounding said lamp socket, the lower portion of said shell being trifurcated and flared outwardly to provide a 3-point seat for said unit and alternate openings to permit insertion of said members in said unit, a cylindrical perforated

sleeve member mounted on and around said shell, the lower portion thereof being flared out to form an enlarged peripheral cylindrical portion adapted to engage a terminal flange on said suspended unit, when said unit is seated on said shell, to prevent lateral movement thereof, and a heat-insulating

packing member depending on said shell and socket between said trifurcated seat and above the perforations in said shell.

In testimony whereof, I have hereunto set my hand.

SAMUEL G. HIBBEN.
